UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

TRIPOD-MOUNTING FOR AUTOMATIC GUNS.

1,093,319.

Specification of Letters Patent. Patented Apr. 14, 1914.

Application filed July 14, 1910. Serial No. 571,887.

To all whom it may concern:

Be it known that we, ARTHUR TREVOR DAWSON, knight, and GEORGE THOMAS BUCKHAM, both subjects of the King of

5 Great Britain, residing at 32 Victoria street, Westminster, in the county of London, England, have invented certain new and useful Improvements in Tripod-Mountings for Automatic Guns, of which the following is

10 a specification.

This invention relates to tripod mountings for automatic guns, and is more particularly applicable to mountings of the kind in which the gun is trunnioned in a 15 top carriage which is capable of lateral displacement for training about a pivot carried by the frame or casing to which the trail and the front legs of the tripod are pivotally attached, the said trail and the 20 front legs being connected with gearing contained in the aforesaid frame or casing which enables the adjustment of the trail and legs to be effected simultaneously within wide limits. When mountings of this 25 kind are employed on sloping ground and after the elevating gear has been operated to bring the sights on the object, the aforesaid pivot about which the gun moves laterally is not vertical, with the result that 30 the muzzle of the gun does not move in a horizontal plane during training.

According to the present invention the training pivot about which the gun moves laterally is made adjustable with respect to 35 the frame carrying the trail and front legs of the tripod, so that the said pivot can be set in the vertical position and enable the gun to be trained in a horizontal plane whatever be the slope of the ground upon 40 which the tripod is standing. The aforesaid top carriage with its elevating gear and a member carrying the training arc, may be mounted in guides formed on the frame or casing containing the adjusting 45 gear for the trail and front legs of the tripod. The said training arc member may be formed with a bearing to receive the training pivot which may be suitably connected to the upper carriage. The training 50 angles are marked on the training arc, and in order to limit the training movement of

the gun between any desired points, two stops may be provided which are adjustably mounted on the training arc.

In order that our said invention may be 55 clearly understood and readily carried into effect, we will describe the same more fully with reference to the accompanying drawings, in which:

Figure 1 is a side elevation partly in section of the mounting constructed in accordance with the present invention. Fig. 1^a is a section on the line 1, 1, of Fig. 1. Fig. 2 is a plan with the gun removed from the mounting. Fig. 3 is a side elevation 65 partly in section showing the position of the parts when the mounting is standing on ground sloping at an angle about 45°, the training pivot having been adjusted so that it occupies a vertical position. Fig. 4 is a 70 diagrammatic view showing on a smaller scale the gun and its mounting in the position illustrated in Fig. 3. Fig. 5 is a plan of the training arc showing the adjustable stops. Fig. 6 is a vertical section on the 75 line 1, 1, of Fig. 5. Fig. 7 is a plan showing a portion of the mounting and the handle for actuating the adjusting mechanism of the trail and legs. Fig. 8 is a similar view with the handle removed and the ammunition tray or box substituted therefor.

A is the gun mounted on the pivot pin or trunnion A', B is the top carriage, B' is the elevating screw carried thereby, C is the training arc member, D is the frame or casing formed with a bearing to carry the training pivot B² of the top carriage B, E is the trail and E' E' are the front legs of the tripod, and F, F', F^x are respectively the screw, the crosshead, and the actuating 85 handle appertaining to the adjustable gear for the said trail and legs.

The aforesaid frame or casing D comprises two side plates which are formed at their upper portions with curved guides d 95 for the reception of the training arc member C which is formed with flanges as shown in Fig. 1^a. The training arc member also carries a clamping device C' which may be of the eccentric type actuated by the handle 100 C^x, the said clamping device coöperating with an arc D' on the frame or casing D to

securely retain the top carriage B and the training arc member C in the adjusted position with the training pivot vertical. The said arc D' may be formed with serrations 5 to insure a better grip being obtained between the member C³ (Fig. 1^a) carried by the clamping device, and the arc D'. The frame or casing D is provided with wheels G mounted on an axle G' to which two 10 cranks g g are connected, the said cranks being mounted in the frame or casing D in the manner previously proposed by us so that the wheels can be adjusted relatively to the mounting; these wheels and the means 15 for adjusting them do not form part of our present invention.

The training arc C² has the training angles marked thereon, and in order to limit the lateral movement of the gun between any 20 two predetermined points on this arc two spring controlled plungers c c (Figs. 2, 5 and 6) are carried by casings c' c' which are adjustably mounted on the arc C². Each of the plungers c is under the control of a 25 spring c^x the lower end of which bears upon a stud c² fixed in the casing c', the plunger c being formed with a slot c³ to allow for the vertical movement of the said plunger over the stud c². The arc C² is formed with 30 teeth on the lower part of its periphery and with these teeth a projection c⁴ on each of the spring plungers c is normally adapted to engage, the casings c' being thereby held in the desired position on the arc C² and act 35 as stops to limit the lateral movements of the gun. When it is desired to adjust one or other of the casings c' on the said training arc the plunger c is depressed against the resistance of its spring c^x thereby moving 40 the projection c⁴ out of engagement with the teeth on the arc and rendering the casing c' free to be moved to the required position on the said arc, whereupon when the pressure on the plunger c is released, the projection 45 c⁴ reengages with the teeth on the arc C² and the casing c' is held rigid therewith as aforesaid. The top carriage B is adapted to be clamped to the training arc C² in any desired position by means of a handle C^{xx} 50 appertaining to the usual eccentric clamping device.

By means of our improved arrangement if the tripod mounting should be standing upon sloping ground and thus cause the 55 training pivot to lie at an inclination the said pivot can be readily caused to assume the vertical by loosening the clamping device C' and turning the upper carriage and training arc about the curved guides d of 60 the frame or casing D, after which the clamping device is tightened again to secure the parts in this position with the training pivot vertical.

It is desirable in order that the feed mechanism shall not have to lift a long and consequently heavy portion of the belt of cartridges for the said belt not to come into contact with the ground; for this purpose we provide an ammunition tray or box L (Figs. 4 and 8) adapted to be mounted on 65 the hexagonal spindle L' of the trail and leg adjusting mechanism. The actuating handle L² of said mechanism is provided with a spring controlled catch l (Fig. 7) having a hook shaped end l' which engages 70 in one or other of a series of holes or recesses l² in the spindle L', the latter being formed with an axial hole for the reception of the said catch l. The ammunition tray or box L (Figs. 4 and 8) is furnished with a 80 boss L^x provided with a spring controlled catch l^x similar to the aforesaid catch l of the handle L² and adapted to engage in one of the holes or recesses l² on the spindle L'. When the handle L² is not in use it may be 85 carried by a pin or the like on the frame or casing D', the catch l serving to retain it in position by engaging with a suitable depression in the said pin. It will be understood that the handle L² of Fig. 7 has the same 90 function as the handle F^x of Fig. 2.

What we claim and desire to secure by Letters Patent of the United States is:—

1. In a tripod mounting for automatic guns, the combination of a top carriage, a 95 training pivot, a trail and legs, an adjusting gear for the said trail and legs, a casing carrying said adjusting gear, and guides on said casing upon which the said top carriage and the training pivot can be adjusted with 100 respect to the said casing to cause the said pivot to occupy a vertical position.

2. In a tripod mounting for automatic guns, the combination of a top carriage, a training pivot, a trail and legs, an adjusting 105 gear for the said trail and legs, a casing carrying said adjusting gear and comprising side plates provided with curved guides, a training arc, and a member carrying 110 said training arc and engaging in said curved guides.

3. In a tripod mounting for automatic guns, the combination of a top carriage, a training pivot, a trail and legs, an adjusting 115 gear for the said trail and legs, a casing carrying said adjusting gear and comprising side plates provided with curved guides, a training arc, a member carrying 120 said training arc and engaging in said curved guides, and a clamping device for retaining said training arc member in the adjusted position.

4. In a tripod mounting for automatic guns, the combination of a training pivot of the gun, a trail and legs, means whereby 125 the said pivot can be adjusted with respect

to the mounting to occupy a vertical position when the mounting is standing on sloping ground, a receptacle for the ammunition belt, gear for adjusting said trail 5 and legs, said gear including a spindle, and means for detachably connecting the said receptacle to the said spindle.

In testimony whereof we affix our signatures in presence of two witnesses.

ARTHUR TREVOR DAWSON.
GEORGE THOMAS BUCKHAM.
